Dec. 1697

John G. Marshbank of Lancaster Penn.
assignor to himself and
Wm. McCombs of Lancaster Penn
Letters Patent No 1697 - Dated Dec 16. 1862

The schedule referred to in these Letters Patent and making part of the same.

To all whom it may concern:

Be it known that I, John G. Marshbank, of the City of Lancaster, in the County of Lancaster and State of Pennsylvania, have invented or produced a new and original design in alto-relievo, for the ornamentation in the front and sides or doors of a cook stove; and I, therefore, declare that the following is a full and exact description of the same, reference being had to the accompanying drawings, making apart of this specification, in which figure 1 shows the configuration of the front, door, and design of the parts in place (shown in perspective,) Figure 2 the design on the side doors, and panels, clearly showing the raised ornaments on the several doors and panels.

What I claim as my invention, and desire to secure by letters patent, is,

The arrangement of the ornamental figures, on the front, side panels, and doors as represented in the accompanying drawings, forming the ornamental design for the doors of a cook-stove.

Witnesses
Chas. H. Fraley
Jacob Stauffer.

J. G. Marshbank.
